UNITED STATES PATENT OFFICE.

FRANK BEEMER, OF PHILADELPHIA, PENNSYLVANIA.

LATCH.

Application filed March 10, 1922. Serial No. 542,638.

This invention is a latch characterized, in its preferred form, by a flanged bolt adapted to oscillate about its axis as well as to reciprocate longitudinally in a pressed metal housing having reversely disposed cams for operating the bolt in reversed positions therein in combination with a keeper adapted to be engaged by the bolt so as to be drawn up and held against lateral or longitudinal movement with relation to the bolt.

The primary object of my improved construction is to provide a simple and strong device that cannot be opened from the outside and can be applied to sliding or swinging doors, windows or the like, so as to secure them in closed position, as also to draw them tightly against their bearings.

In the accompanying drawings, Fig. 1 is a horizontal sectional view taken through a hinged door secured in closed position by my improved lock, which is shown in part sectional plan; Fig. 2 is a horizontal sectional view through a sliding door showing my improved lock applied thereto in part sectional plan; Fig. 3 is a front elevation of my improved lock applied to a door jamb and door shown in broken part sectional elevation; Fig. 4 is a sectional view taken through the housing and bolt on either of the lines 4*-4* of Fig. 3; Fig. 5 is a sectional view taken through the housing and bolt on the line 5*-5* of Fig. 3; Fig. 6 shows a broken section of a door together with an elevation of the keeper and a section of the bolt disposed therein in the unlocked position, and Fig. 7 is a view similar to Fig. 6 with the bolt turned in locked position.

The latch, in the form thereof illustrated in the drawings, comprises a sheet metal housing cut and pressed to shape so as to provide in an integral construction the flat parallel bearings 1 lying in a plane and the arch 2 connecting them and extending parallel thereto. This arch has the transverse sections 3 separated therefrom on parallel lines 4 and bent downwardly to semi-cylindrical form to provide bearings for cooperation with the semi-cylindrical bearings 5 formed by the crown of the arch. An opening 6 is formed in the arch midway of its length and has the oppositely inclined edges or cams 7 having the terminals 7' which may be approximately at right angles to the length of the arch. A bolt 8 is adapted to move longitudinally and rock in the bearings 4 and 5 and a stem or han-

dle 9 is fixed to the bolt transversely there-to so as to project through the opening 6 and act against a cam 7. An end of the bolt has thereon the flange or cam 10 which is adapted to pass through an opening 11 in a keeper 12 and to be turned into position for engaging the keeper so as to prevent the withdrawal of the bolt therefrom.

The housing has a lug 13 cut and bent up from the bearing 1 adjacent to the contracted lower end of the opening 6 so as to lie midway between the cams 7, this lug containing an opening 14 adapted for the passage of the yoke 15 of a lock 16 for securing the stem or handle 9 to the yoke and fixing the bolt 6 in the securing position.

It will be observed that as the terminals 7' of the cams 7 are disposed substantially at right angles to the bolt 8 they effect an approximately square engagement with the stem or handle 9 to retain the same in position for holding the bolt in the secured position.

The housing, by reason of its symmetrical construction, is adapted for use with the bolt in reversed positions so that the latch is applicable to right or left hand connection.

As illustrated in Fig. 1, a door 17 adapted to oscillate upon the hinges 18 is secured in the closed position to the jamb 19 by means of my improved latch. This is effected by passing the screws 20 through the holes 21 in the housing bearings 1 and thence into the jamb to secure the housing thereto. The keeper 22 is screwed to the inner face of the door, adjacent to the jamb by passing through the holes 23 in the keeper and into the door the screws 24, the opening 11 in the keeper being disposed so that the flanged end of the bolt will pass therethrough in the elevated position of the stem or handle 9 and turn in a socket 25 in the door large enough to permit such flange to engage the keeper.

The door being closed and the handle 9 being elevated, the bolt 8 can be shot forward so that the flange 10 passes through the opening 11. The handle 9 is now turned downwardly and the cam 7 acts thereon to draw the bolt back in the housing so that as the flange turns into position for engaging the keeper 12, it is pressed against the same to draw the door firmly against the jamb, the handle engaging the section 7' at the bottom of the cam 7 to hold it in the

desired securing position, where it can be secured by lock 16.

It will be understood that a door, window or the like, when thus secured, is held firmly 5 against its bearing so that a device cannot be entered between the two to undo the lock, rattling is prevented and an approximately air tight or water tight joint can be made.

As illustrated in Fig. 2, the latch is applied to a sliding door 26 by fixing the housing bearings 1 to the jamb 27 and fixing the keeper 22 to the inner face of the edge of the door adjacent to the jamb, by which the flange 10 on the end of the bolt 8 can be engaged within the keeper not only to lock the door against sliding, but also to draw it tightly against its jamb so as to prevent the entry of an opening device to form a tight joint and to prevent rattling.

10 It will be understood that the parts 17 and 26 may be windows as well as doors and that the latch has the same advantages in securing windows as doors.

Having described my invention, I claim:
15 1. A latch having a pressed metal housing

comprising bearings connected by an arch having sections bent downwardly therefrom to provide with said arch a way, said arch having a cam formed therein, transversely to the length thereof, and a bolt adapted to rock and move longitudinally in said way, said bolt having a device projecting laterally therefrom so as to coact with said cam, whereby said bolt is moved longitudinally when it is rocked.

2. A latch having a keeper provided with bearings, one of said bearings having a lug thereon, and an arch connecting said bearings, said arch having sections bent downwardly therefrom to form therewith a way and having therein oppositely inclined cams, and a bolt adapted to rock and move longitudinally in said way, said bolt having a device projecting laterally therefrom so as to coact with one or the other of said cams to effect the longitudinal movement of said bolt and to be locked to said lug.

In testimony whereof I have hereunto set my name this 8th day of March, 1922.

FRANK BEEMER.
